CROSS FOLDING MACHINE

Richard Ludewig, Leipzig, Germany

Application September 25, 1935, Serial No. 42,077
In Germany September 25, 1934

10 Claims. (Cl. 270—62)

The invention relates to a cross folding machine having a blade folding mechanism for the cross fold succeeding a buckling folding mechanism, and consists therein that the stroke of the 5 blade is caused directly, or for example through an automatically disengaging coupling, independently of a definite working tempo by the sheet conveyed up to the front stops of the cross folding mechanism by the closing of the control opening of a suction conduit in which a suction piston (sniffling piston) connected with the folding blade is displaceably arranged. This pneumatic control of the stroke of the blade renders possible, in consequence of its independence of a fixed working 10 tempo and of the lifting eccentric of a control shaft, the adaptation of the capacity of the blade folding mechanism to the higher capacity of the buckling folding mechanism, whilst retaining the advantages of the blade fold as compared with 15 the buckling fold, particularly with thick sheet layers, namely of exact fold and of exact registration. Moreover the pneumatic control has the advantage that the source of power necessary therefor is at its disposal in the air pump of the sheet feeding device, which air pump is existent 20 in any case.

The drawings illustrate a constructional example of the invention.

Figs. 1 and 2 show in diagrammatic representation an elevation and a plan.

Figs. 3 and 4 illustrate respectively a longitudinal section or cross section of the testing device.

Figs. 5-7 inclusive illustrate respectively an elevation, a longitudinal section and a cross section of a control slide member.

Fig. 8 illustrates a modified construction of the testing opening.

Fig. 9 is a diagrammatic plan view similar to Fig. 1 but showing an adjustable suction testing opening; and

Fig. 10 is a similar view showing an adjustable suction testing opening of the modification of Fig. 8.

The sheet is led up over a feed table 1 and arrives, after running through a buckling folder consisting of the buckling rollers 2, 3, the driving roller 4 and the buckling guide 5, and also a parallel folding mechanism with the folding rollers 3, 6 and the buckling guide 1, on conveying bands 8 which lead it to the front stops 9 of the cross folding mechanism consisting of the folding rollers 10 and the folding blade 11. The folding blade 11 is connected with a piston rod 12 50 of a sniffling piston 13, which is guided in a sta-

tionary shifting cylinder 14 so as to be vertically displaceable. Folding blade, piston rod and piston are held by means of a spring 15 in a position of readiness.

The cylinder space located beneath the piston is connected by means of a conduit 16 with an air pump 17. A rotary slide valve 18 is arranged in this conduit which, in one position, shuts off the conduit 16 from the outer air and in the other position connects the conduit 16 with the outer air. The rotary slide valve 18 is mounted on a tubular conduit part 19 in the wall of which a number of slits 20 are arranged with which in the open position of the slide valve 18 similar slits 21 of the latter come into register, so that the free air can pass without hindrance into the suction conduit. In this position of the slide valve the sniffling piston 13 remains uninfluenced by the suction conduit of the pump.

The rotary slide valve 18 is provided with a short arm 22 which is pivotally connected with a piston rod 23 of a shifting piston 25 displaceable in a stationary cylinder 24. A spring 26 which is mounted on the piston rod 23 maintains the rotary slide valve in the open position and thus keeps the piston 25 in the "ready" position. The space in the cylinder 24 on the working face of the piston 25, is likewise connected with the suction side of the air pump 17 by means of a conduit 27.

The conduit 27 is connected with the outer air by means of a testing opening 28 in a conduit member which is arranged closely in front of a front stop 9. In the constructional example illustrated in Fig. 3, said conduit comprises a rotating suction conveying wheel, the holes 28 of which coming one after the other into the apex position place the conduit 27 with short interruptions in connection with the free air. The suction conveying wheel consists of the two hub parts 29, 30 which are rotatably arranged on a pipe 27a inserted in the conduit 27 and serving as an axle, and a cover 31 connecting said hubs and having openings 28 therein. The one hub 29 of the suction conveying wheel is provided with a sprocket gear 32 which is connected by means of a driving chain 33 with a chain wheel 35 mounted on the driving shaft 34 of the bands. The cover 31 of the conveying wheel has an air tight engagement with a disc 36 fixedly mounted on the conduit pipe 27a within said wheel, which disc normally covers all of the holes 28 of the cover except the top hole. The top hole is in connection, by means of a recess 37 of the disc 36, with the hollow center space of the suction con- 50

veying wheel and also by means of radial bores 38 in the wall of the pipe 27a, with the inner space of the conduit 27.

The sheet after passing through the buckling folding mechanism is led by the conveying bands 8 to the front stops 9 of the cross folding mechanism. This position is shown by the broken lines in Fig. 2. When it is in this position the sheet closes the testing opening 28 at the top of the 10 suction conveying wheel 31, whereby the suction action produced by the pump 17 in the pipe system 27, 27a is slightly strengthened. This strengthening of the suction action suffices to cause a displacement of the piston 25 in the 15 cylinder 24, by means of which the rotary slide valve 18 is turned so far that the slit opening 20 of the conduit part 19 in the suction pipe 16 leading to the suction cylinder 14 is closed. Now, 20 the whole suction action of the pump comes into operation and causes a displacement of the piston 13 which results in the stroke of the folding blade 11.

Inasmuch as the suction action at the testing opening 28 is very small, it does not hinder the 25 drawing off of the sheet by the folding roller 10, and inasmuch as the control opening is arranged close to the side edge of the sheet, the testing opening 18 is re-opened immediately after the stroke of the folding blade. On cessation of the 30 suction action in the cylinder 24 the piston 25 is returned to its normal position under the influence of the spring 26. Simultaneously the rotary slide valve 18 is returned to the original position in which the interior of the conduit 16 35 has an open connection with the air, through the medium of the slits 20, 21.

Consequently, the suction action in the suction cylinder 14 is also eliminated and the piston 13 together with the piston rod 12 and the folding 40 blade 11 are carried back by the spring 13 into the position of readiness.

The folding process may take place in such manner that the folding blade does not strike so far in between the folding rollers that the sheets 45 are drawn in by the pinching action alone of the folding rollers, but only presses the sheets in to an extent such as is necessary in order that the sheets may be sucked up and drawn in by a folding roller constructed in known manner as a suction roller. This constructional possibility is 50 indicated in Figs. 1 and 2. The one roller 10 is constructed in a manner known per se as a suction conveying roller, the stationary core of which is connected by means of a conduit 39 with the air pump. The folding blade 11 is provided 55 on the side directed towards this folding roller with pressing rollers 40, which upon the descent of the folding blade press the sheet on to the folding roller constructed as a suction feed roller, so that it is tightly sucked in on to the roller and is drawn in by the latter.

Naturally the suction roller folding mechanism might be provided with any disposition and arrangement already known in a folding mechanism 65 of this kind. In particular also the pressing rollers 40 may be arranged on both sides of the folding blade and the other roller may likewise be constructed as a suction folding roller.

It is likewise obvious that in the different suction pipe systems, all the known devices for the regulation of the suction action may be employed.

The suction testing openings 28 and 28a, as shown in Figs. 9 and 10, are preferably arranged so as to be adjustable in the direction transversely 70 to the cross fold corresponding to the varying

breadth of the sheet. In certain circumstances it may also be advisable to vary the distance of the testing opening 28 from the front stops 9 with regard to the different nature of the paper, for example by an adjustable arrangement of the 75 front stops.

Means for accomplishing the above noted adjustments are shown in Figs. 9 and 10 where a support 100 is carried by the frame of the machine in any suitable manner. The support 100 10 is slotted as at 101, said slot extending longitudinally of the frame. A collar 102 is slidably mounted on said support and is capable of being adjustably positioned therein by a nut 103. The collar carries a transverse collar 104 in which a 15 transversely extending rod 106 is slidable. Adjustment of the rod 106 is accomplished by the wing nut 105. In Fig. 9, a collar 107 at one end of the rod 106 encircles a pipe 27b.

In Fig. 10, a connection 108 connects the pipe 20 27b with the rod 106. It is readily apparent that the above described structure provides means for adjusting the testing openings 28 and 28a both longitudinally and transversely of the frame of the machine.

It is further not absolutely necessary to arrange the testing opening in a suction conveying wheel according to the peripheral velocity of the sheet, but in many cases a stationary testing opening such as is shown in Fig. 8 will suffice and 30 will permit, with the small strength of the suction action, of a reliable conveyance of the sheets to the front stops.

I claim:—

1. In a sheet folding machine, a pair of folding 35 rollers, means for feeding a sheet in the zone of action of said rollers, a stop for limiting the movement of said sheet, a vertically movable blade for creasing said sheet between said rollers, a suction actuated piston rigidly connected to said 40 blade and adapted to move the same to crease said sheet, a suction line connected to the cylinder of said piston, a portion of said line being formed to provide an opening therein, and said opening being adapted to be overlaid by an edge 45 portion of said sheet whereby to seal said opening and increase the suction in said line enough to actuate said piston.

2. In a sheet folding machine, a pair of folding 50 rollers, means for feeding a sheet into the zone of action of said rollers, a vertically movable blade for creasing said sheet between said rollers, a suction actuated piston for actuating said blade, a normally open suction circuit leading from a suction creating source to said piston, said circuit being formed to provide an opening therein at a point flush with the plane of and within the limits of travel of said sheet so as to be adapted to be overlaid by a portion of said sheet at a predetermined point in the travel thereof to close 60 said suction circuit and actuate said piston.

3. In a sheet folding machine including sheet advancing means, folding rollers, suction operated sheet creasing means and a normally open suction circuit for actuating said means, said circuit being formed to provide an opening in the plane of and within the limits of the path of advance of the sheets and adapted to be overlaid by each of said sheets at a predetermined point in said advance to close said circuit and actuate 70 said creasing means.

4. In a sheet folding machine including sheet advancing means, suction operated sheet folding means and a normally open suction circuit connecting said means to a suction creating source, 75

said circuit being formed to provide an opening in the plane of and within the limits of the path of advance of the sheets and adapted to be overlaid by each of said sheets at a predetermined point in said advance to close said circuit and actuate said folding means.

5. The structure of claim 4, and said portion of said circuit providing said opening being adapted to be adjusted laterally and longitudinally in a horizontal plane.

6. The structure of claim 4, and the actuation of said folding means causing movement of said sheet to uncover said opening automatically thereby opening said circuit and breaking the same.

7. In a sheet folding machine including sheet advancing means, suction operated sheet folding means, and a suction circuit connecting said means to a suction creating source, a valve in said circuit, said valve being normally positioned to break said circuit, suction means including a normally open and relatively weak circuit for closing said valve, circuit closing means in said second

circuit, said circuit closing means being positioned in the plane of and within the limits of the path of advance of the sheets and adapted to be overlaid by each of said sheets at a predetermined point in said advance to close said second circuit and actuate said valve to close said first circuit to actuate said folding means.

8. The structure of claim 7, and said circuit closing means in said second circuit being adapted to be adjusted laterally and longitudinally in a horizontal plane.

9. The structure of claim 7, said circuit closing means in said second circuit being adapted to be adjusted laterally and longitudinally in a horizontal plane, and the actuation of said folding means causing movement of said sheet to open said circuit closing means automatically and break said second circuit.

10. The structure of claim 1, and said portion of said line containing said opening being adjustable to permit its being positioned on said machine.

RICHARD LUDEWIG.
